JULIUS H. BECKER, OF SAN FRANCISCO, CALIFORNIA.

LIQUID-HYDROCARBON FURNACE.

1,068,037.

Specification of Letters Patent. Patented July 22, 1913.

Application filed January 21, 1913. Serial No. 743,295.

To all whom it may concern:

Be it known that I, JULIUS H. BECKER, a citizen of the United States, residing in the city and county of San Francisco and 5 State of California, have invented new and useful Improvements in Liquid-Hydrocarbon Furnaces, of which the following is a specification.

This invention relates to an auxiliary furnace especially constructed to handle liquid-hydrocarbons, such as crude or fuel oils.

The main object of this invention is to provide a simple, substantial and durable furnace of the auxiliary type, wherein high 15 temperatures may be generated without excessively exposing any particular part of the furnace.

Another object of this invention is to provide outside means for supporting the main 20 arch of the furnace so as to eliminate the use of any inside supports which would sooner or later deteriorate by constant exposure to the heat in the furnace and leave the arch in a weakened condition, when it 25 would finally collapse, a further object being to so arrange the draft controls and flues of the furnace, that the products of combustion generated in the front half of the furnace may be conveyed to the point of 30 discharge without disturbing the flame area of the rear part of the furnace.

The invention consists of the parts and the construction and combination of parts as hereinafter more fully described and 35 claimed, having reference to the accompanying drawings, in which:

Figure 1 is a longitudinal section on the line X—X of Fig. 3. Fig. 2 is a cross section on the line V—V of Fig. 3. Fig. 3 is a 40 plan section on the line Y—Y of Fig. 1. Fig. 4 is a perspective view showing the firing plate support or base. Fig. 5 is a plan showing the draft regulating means controlling admission of draft through the 45 central opening.

Referring to the drawings "A" indicates the shell of a furnace which may be constructed of any suitable refractory material, such as fire brick or the like, and which may 50 be inclosed by a suitable metal framework or casing, as at 2.

3 indicates the central or main combustion chamber of the furnace, in the lower and center portion of which is mounted an 55 atomizing or firing plate 4, to which a suit-

able liquid-hydrocarbon fuel, such as crude oil, is delivered through a central opening 5 formed in the top portion 6, or arch of the furnace.

9 indicates a water supply pipe controlled 60 by a valve 10, and 7 the oil conveying pipe controlled by a valve 8; the pipes 7 and 9 meeting in a delivery pipe 11, the discharge tip 12 of which lies just above the open top of the central opening 5.

Leading from the exterior of the shell and controlled by a door 13 is a passage 14, formed in the base of the shell, which opens interiorly under the plate 4; the plate being so positioned as to form a roof or covering 70 for the passage. The inner opening or throat of this passage is slightly enlarged to receive a rectangularly shaped hollow metal base 15, which is provided for the purpose of supporting the generating or firing plate.

The firing plate 4 and base should preferably be made of cast steel or like material, which will be able to stand the high temperatures of the furnace without cracking 80 or bending out of shape; this being of great importance when one considers that any slight bending or warping of the base and plate might cause an uneven flow or discharge from the plate, with a consequent inequality of flame distribution. The size of the base and plate are such that they may be removed through a door 16 closing an opening 17 formed in the front part of the 85 furnace.

For the purpose of producing a perfect and uniform combustion in the furnace, and also for the purpose of conveying the products of combustion generated in the front half of the furnace to the point of discharge, indicated at 18, without interfering with the flame area in the rear half of the combustion chamber, I have shown the furnace as being provided with two side flues 19 and 20 through which the products in 100 the front half of the furnace may be conveyed as indicated by the arrows, to the point of discharge without disturbing the flame area of the rear half of the furnace. The rear portion of the combustion chamber 105 is also provided with a discharge opening, indicated at 21, of a sufficient restricted area to balance or equalize the discharge of the products of combustion through the different flues.

For the purpose of supporting the main arch over the combustion chamber, I have provided the head blocks 22, and a suitable number of tie-rods 23; the head blocks being suitably supported in the metal frame or casing inclosing the furnace. This construction entirely eliminates the necessity of providing inside supports, which would sooner or later deteriorate by constant exposure to the heat within the furnace, and thereby leave the arch in a weakened condition so that it would finally collapse. It can therefore be seen that the walls 24 and 24' separating the side flues 19 and 20 from the main combustion chamber, may be entirely destroyed without weakening the main arch.

In operation, a temporary fire is made from any suitable fuel placed in the passage 14, below the generator plate; all draft openings except the door 13 being closed. This fire is continued until the plate 4 is sufficiently heated to vaporize the water and oil when delivered to the plate. The oil and water in the right proportions are then gradually turned on, and are ignited by the flames discharging around the plate 4 from the lower preliminary heating chamber 14; the base portion 15 being formed with escape passages 15^a for this purpose. The moment sufficient heat has been generated within the main combustion chamber to support combustion, the fire within the temporary heating chamber 14 may be drawn and the door 13 closed. The main draft necessary for combustion is then admitted with the falling fuel mixture through the central opening 5; this draft being regulated by a pair of plates 25, slidably mounted in a suitable metal frame 26 mounted in the upper end of the central opening. The fall of the mixed oil and water from the tip 12 to the plate 4 is sufficient to cause it to spatter and atomize. The mixture is thus evenly spread over the plate and burns with a flame which spreads evenly to all sides of the combustion chamber; the products of combustion generated in the front half of the furnace being carried by the draft through the side flues 19 and 20, from which they are conveyed to the main discharge passage 18, where they unite with the products of combustion from the rear half of the combustion chamber, which are discharging through the restricted opening 21; this opening being just sufficiently restricted, as before described, to cause an equal distribution and draft through the various flues.

The furnace is neat and substantial in construction, efficient and reliable in action, and takes no more space than other similar furnaces. The materials and finish of the several parts of the furnace are such as the experience and judgment of the manufacturers may dictate.

Having thus described my invention, what

I claim and desire to secure by Letters Patent, is:

1. A liquid-hydrocarbon furnace comprising a shell inclosing a combustion chamber; an arch covering said chamber, a metal frame inclosing the furnace shell, means carried by the frame for supporting the arch of the combustion chamber, a temporary heating chamber formed in the shell below the combustion chamber leading from the exterior and opening up through the floor of the combustion chamber, an enlarged throat portion formed in the inner opening of said chamber; a base mounted in the enlarged throat portion, a firing plate resting on said base, a central draft and fuel feeding passage formed in the arch communicating with the combustion chamber and opening out through and above the arch, means for delivering fuel into said opening so that it will fall upon the firing plate, a pair of flues formed in the sides of the furnace connecting the front portion of the combustion chamber with a main discharge opening in the rear of the furnace, and a contracted passage formed in the rear of the combustion chamber communicating with the side flues.

2. A liquid-hydrocarbon furnace comprising a shell inclosing a combustion chamber, an arch covering said chamber, a metal frame inclosing the furnace shell, means carried by the frame for supporting the arch of the combustion chamber, a temporary heating chamber formed in the shell below the combustion chamber leading from the exterior and opening up through the floor of the combustion chamber; an enlarged throat portion formed in the inner opening of said chamber; a base mounted in the enlarged throat portion, a firing plate resting on said base, a central draft and fuel feeding passage formed in the arch communicating with the combustion chamber and opening out through and above the arch, means for delivering fuel into said opening so that it will fall upon the firing plate, discharge openings formed in the base below the plate, a pair of flues formed in the sides of the furnace connecting the front portion of the combustion chamber with a main discharge opening in the rear of the furnace, and a contracted passage formed in the rear of the combustion chamber communicating with the side flues.

3. A liquid-hydrocarbon furnace comprising a shell inclosing a combustion chamber, an arch covering said chamber, a metal frame inclosing the furnace shell, means carried by the frame for supporting the arch of the combustion chamber, a temporary heating chamber formed in the shell below the combustion chamber leading from the exterior and opening up through the floor of the combustion chamber, an enlarged throat portion formed in the inner opening of said chamber; a base mounted in the en-

larged throat portion, a firing plate resting on said base, means for controlling the draft passing through the opening into the combustion chamber, a central draft and fuel feeding passage formed in the arch communicating with the combustion chamber and opening out through and above the arch, means for delivering fuel into said opening so that it will fall upon the firing plate, discharge openings formed in the base below the plate, a pair of flues formed in the sides of the furnace connecting the front portion of the combustion chamber with a main discharge opening in the rear of the furnace, and a contracted passage formed in the rear of the combustion chamber communicating with the side flues.

4. A liquid-hydrocarbon furnace including an arched combustion chamber having passages formed on either side from front to rear; a centrally located firing plate upon which the liquid fuel is dropped, and a preliminary heating chamber beneath the plate, said passages serving to convey the products of combustion from the front of the combustion chamber around the sides to the rear without crossing the plate. 20 25

In testimony whereof I have hereunto set my hand in the presence of two subscribing witnesses.
